UNITED STATES PATENT OFFICE.

FREDERICK CARLYLE RILE, OF CHICAGO, ILLINOIS.

DESIGN FOR A CUFF BUTTON OR THE LIKE.

Application filed May 4, 1928. Serial No. 26,574 Term of patent 14 years.

To all whom it may concern:

Be it known that I, FREDERICK CARLYLE RILE, a citizen of the United States, residing at Chicago, in the county of Cook and State of Illinois, have invented a new, original, and ornamental Design for Cuff Button or the like, of which the following is a specification, reference being had to the accompanying drawing, forming part thereof.

I claim:
The ornamental design for a cuff button or the like as shown.

FREDERICK CARLYLE RILE.
